UNITED STATES PATENT OFFICE.

GEORGE W. CAMPBELL, OF HARTFORD, CONNECTICUT, ASSIGNOR TO UNDERWOOD TYPEWRITER COMPANY, OF NEW YORK, N. Y., A CORPORATION OF DELAWARE.

TYPEWRITING MACHINE.

Application filed May 10, 1922, Serial No. 559,693. Renewed June 16, 1925.

To all whom it may concern:

Be it known that I, GEORGE W. CAMPBELL, a citizen of the United States, residing in Hartford, in the county of Hartford and State of Connecticut, have invented certain new and useful Improvements in Typewriting Machines, of which the following is a specification.

The present invention relates to sound-deadening casings for typewriting machines; and more particularly to the type of casing into which the machine is inserted from the top; the casing having a cover which may be opened to permit of placement and removal of the machine, and to permit of access to the machine for erasures and other purposes. Casings of the character mentioned have been provided with spring-devices for assisting in opening the casing-cover; also with adjustable means for locating the rear feet of the machine; and with various means for holding lining-sheets of sound-deadening material in place.

An object of the invention is the provision of a spring-device, for automatically swinging open the casing-cover, around pivots at the rear of the casing, whenever the cover is unlocked; such spring-device being adjustable as to the tension thereof, to accord to the weight and leverage involved; also to accord to variable frictional resistance at the casing-joints; and to accord to the action of a buffer combined therewith to prevent shocks in the cover-opening operation.

A further object of the invention is the provision of an adjustable foot-locator for the machine, of cheap and simple construction, easily set to the casing, and, which, when so set, will not be accidentally deranged or disjointed either in handling of the casing, insertion of the machine, or manipulation to adjust the same. In the form of the invention, hereinafter described in detail, the locator is a single, somewhat flexible sheet-metal stamping, pivotally secured at one end to the rear wall of the casing, whereby it may be swung out of the way, and having means at its other end for locking it against movement after it is in place against the foot of the machine.

Another feature of the invention is the provision on the lower edge of the casing-body, preferably as part of a casting form-

ing the casing-body, of a peripherally-extending rib or flange forming with the wall of the casing a channel in which the lower edges of sheets of sound-deadening lining-material may be held against displacement.

Other features and advantages will herein-after appear.

In the accompanying drawings,

Figure 1 is a view, in cross-sectional side elevation, through the casing; the machine being indicated in dot-and-dash lines therein.

Figure 2 is a broken view, in cross-sectional side elevation, of the casing, partly open, and showing the cover-opening device.

Figure 3 is a top plan view of the casing-body; the casing cover being shown, in part, at the left-hand side, to illustrate the connection thereto of the cover-opening device, which latter as well as the rear feet-locators and lining-holder are shown in detail.

The casing is shown as comprising two principal castings, one of which 10 constitutes the body of the casing, and the other of which 11 constitutes a cover hinged at 12 to the body-portion. The body and cover castings have linings 14 and 15, respectively, of sound-deadening material. The body-portion of the casing is shown as having a floor or bottom 16, of sound-deadening material, secured to the casting in any suitable manner, as by means of screws 17. The cover of the casing is provided with a window-pane 18, of glass or other transparent material, to permit the operator to observe the printing effected within the casing. The pane 18 is held in an opening in the cover-casting in any suitable manner.

The machine 19 within the casing is provided with the usual front feet 20 and rear feet 21. The keyboard-extension 22 of the machine projects through a suitable opening 23 in the front wall 24 of the casing-body. The typewriter-carriage 25 is mounted to have letter-feed and return movements on the main frame of the machine, and has mounted thereon a carriage-release-lever 26, a line-space lever 27, and a carriage-return-arm 28. In Figure 1, these levers are shown as projecting to the outside of the front wall of the casing, so as to be accessible to the operator. Since these levers must move with the carriage, the front wall of the casing must be slotted horizontally and longitudi-

nally thereof. In Figure 1, this slot is shown at 29 as formed by a bead 30 on the forward lower edge of the cover and by a bead 31 on the upper edge of the front wall 24 of 5 the casing-body. The slot 29 is, however, practically closed by two resilient, flexible cushions 32 and 33; the cushion 32 being attached to the bead 30 on the cover, and the cushion 33 being attached to the bead 31 on 10 the front wall of the casing-body. The cushions, in effect, close the slot 29, being in contact with each other except where the levers 26, 27 and 28 protrude between the same. The yieldable, flexible character of 15 the cushions permits movement of the levers therealong as the carriage is moved in one or the other direction.

When the casing-cover is open, the typewriting machine may be inserted into the 20 casing through the open top of the casing-body. In the form of the casing shown, the typewriter is inserted with its keyboard-extension tilted downward and forward. Thus tilted, the keyboard-extension is passed 25 through the hole or opening 23 in the front wall 24 of the casing; the side plates of the main frame of the typewriting machine being received in slots (not shown) in a cross-piece 34 of the casing-body below the keyboard. The keyboard-extension is brought 30 forward through the opening 23, and the front of the machine lowered until the front feet 20 thereof enter recesses in locators 35, which are shown in Figure 3 as horizontal 35 lugs forming part of the casting of the casing-body. The recesses in the locators 35 are curved in conformity with the curvature of the front feet 20.

After the feet 20 are centered in the locators 35, the rear of the machine is lowered 40 to bring the rear feet 21 to rest on the base-piece 16. When the rear feet 21 are thus seated on the base 16, they should find themselves in recesses 36 (see Figure 3) of locators at the rear of the casing. In Figures 45 1 and 3, the locator of the present invention is shown as an abutment in the form of a sheet-metal, somewhat resilient, strip 37, curled at the rear end to embrace a pin 38. The pin 50 38 is threaded at its bottom, at 39, to screw into a lug 40, forming part of the casting of the casing-body; and is provided with a slotted head 42, which serves to hold down the abutment-member 37. At its other end, the 55 member 37 carries a pin 43, which passes through a slot 44 in a lug 45, which projects inward from the side wall of the casing-body and is part of the body-casting. The pin 43 is threaded to receive a thumb-nut 60 46, which, when tightened against the side of the lug 45, serves to hold the locator 37 against movement. When the nut 46 is loosened, the locator may be swung on the pin 43 as a pivot, and, being somewhat resilient, 65 may be moved laterally along the rear face

of the lug 45. This movement or play of the locator permits the recessed foot-holding part thereof to be adjusted laterally to accommodate and engage the corresponding foot of the typewriting machine. When 70 such adjustment is effected, the thumb-nut 46 is tightened to hold the locator in correct position.

In practice, the thumb-nuts 46 may be loosened or swung out of the way before the 75 machine is inserted. After the correct positions for the rear feet of the machine have been determined by the engagement of the front feet of the machine with the front locators, the rear locators are moved by hand 80 into engagement with the rear feet, and the nuts 46 then tightened. If it is found, in lowering the rear of the machine, that the rear feet strike the top of the rear locators, these may first be moved out laterally, to 85 permit the rear feet of the machine to be set down upon the base-piece 16, and then they may be moved laterally inward to engage and hold the feet.

The lower edge of the casting, forming 90 the casing-body, has formed thereon, entirely around its periphery, a flange which is first directed inwardly, as at 47, and then upwardly, as at 48, to form a channel, in which the lower edges of the lining-pieces 95 14 of the casing-body may be set; and by means of which such lining-pieces are held against displacement when so set. In Figure 1, the rear lining-member 14 is shown in position in the channel formed by the peripheral flange or rail 48; and, in Figure 3, one of the front lining-members 14 is shown as extended down along the floor of the left-hand overhang 50 into its retaining channel at the bottom of the casing-body. The overhanging portions 50 of the casing-body are 100 for the well-known purpose of providing space for movement of the carriage on the machine; and, for the same reason, the cover is of the width represented by the overhangs 110 50, rather than of the width represented by the lower portion of the casing-body, which has only to accommodate the stationary frame of the typewriting machine.

For causing the cover automatically to 115 open, when free to do so, there is provided a spring-device consisting of an arm 51, pivoted on a bolt 52, one end of which bolt is fixed in an ear 53, formed on the casting 10, the other end of which is fixed in a recess in the 120 end wall of the casting 10. The ear 53 projects through a cut in the rear lining-member 14, and the bolt passes through a hole in the end lining-member 14. The arm 51 has an elongated slot 54 therein, and through this slot projects a roller 55, carried on a shouldered screw 56, which is threaded into a boss 57, formed on the end wall 58 of the cover-casting 11. Because of 125 the shoulder in the screw 56, the roller 55 130

cannot be jammed against the boss 57, but will turn freely on the screw, so as to eliminate frictional engagement with the cover-lifting arm 51.

5 At its rear end 59, the arm 51 has pivotal bearing on the bolt 52. The right-hand face of the boss on the arm, through which the bolt 52 passes, is toothed, as indicated at 60, and engages a conversely-toothed collar 61, forming part of a sleeve 63, which is mounted both to slide and to rotate on the bolt 52. Embracing the bolt 52 and the sleeve 63 is a coiled spring 64, one end 65 of which passes through a hole in the lug or 15 ear 53 in the rear wall of the body-casting, and is thus anchored to the body of the casing. The other end 66 of the spring 64 enters and is held in a recess in the collar 61. The spring 64 tends to urge the collar 61 20 toward the arm to cause the opposing teeth on these two elements to engage one another and to remain in engagement. The teeth thus in engagement with each other are so directed that there is no tendency of the collar 61 to cam itself out of engagement with the arm 51 under the action of the spring 64. To properly tension the spring 64, the collar 61 may be rotated by a tool, which may be inserted in holes 62. To enable the 25 rotation of the collar by the tool, it is slideable longitudinally on the bolt 52, so that the teeth of said collar may slip by the teeth 60 of the arm 51. By so regulating the tension of the spring, a sufficient force, properly to 30 open the cover, may be obtained; and, on the other hand, the cover may be prevented from opening too violently.

When the arm 51 swings upward and rearward under the tension of the spring 64, it carries the cover with it, by reason of the engagement of the pin and roller, 56 and 55, in the slot 54 in the arm. As the cover swings open, the pin and roller move toward the distal end of the arm. The ends of the 45 slot 54 may serve as stops to determine the open and closed positions of the cover.

A shock-absorber is provided to prevent shocks on the hinges and other parts of the casing when the cover opens under the action of the spring 64. The shock-absorber consists of a cylindrical extension 67 on the distal end of the arm 51, in which cylinder a piston 68 on a pin or shaft 69 is adapted to move. Within the cylinder 67 is a coiled 55 spring 70, one end of which has bearing upon a stud 71, and the other end of which bears upon the piston 68. In Figure 1, the piston 68 is shown as seated against one end of the cylinder 67, and the spring 70 is shown as slack. The pin 69 passes through the end of the cylinder 67 and into the slot 54, where it lies in the path of the roller 55. When the cover is opened, the roller 55 passes along the slot 54 until it engages the 60 end of the pin 69 and starts to compress the

spring 70. From this point on, the spring 70 acts as a buffer, its resisting force increasing as it is compressed by the piston 68. The stud 71, against which the spring 70 bears, is threaded, so that, by turning the 70 same, the tension of the spring 70 and strength of the buffer may be regulated.

For locking the cover against the action of the spring-device, just referred to, there is pivoted at 72, to one of the side walls of the cover, a hook 73, which depends into the body-part of the casing. When the cover is shut and the hook 73 is swung forward, it engages a detent 74, carried by the casing-body. Mounted to be slid rearward 75 and forward in the front wall of the casing-body is a pin 75, carrying on its outer end a finger-piece 76, and having on its inner end a head 77, adapted to engage the end of the hook 73. When the key or finger-piece 76 80 is pressed rearward, the pin 75 disengages the hook from the detent 74 and releases the cover to the action of the opening device, heretofore described. A sleeve 78, mounted in the casing front wall, serves as a hardened 85 bearing for the pin 75. This is employed because the material of the casing itself may not be hard enough to prevent undue wear by the pin 75; and such wear might cause the pin to become loose and inaccurate in its 90 action.

In order that the hook may not be injured by the typewriting machine, in the operation of removing the latter from the casing, and may not be struck by the operator, or otherwise be bent or injured, it is set in a housing. This housing is in two sections, one section 80 being on the cover, and the other section 81, which forms a continuation of the section 80, being on the casing-body. As shown in Figure 1, the housing 80 is of U-shaped sheet-metal, closed at the top, and the housing 81 is likewise in the form of a U-shaped piece of sheet-metal, open at the top and closed at the bottom by the offset side wall 50 of the body-portion of the casing. Within the housing 80 on the cover is also a leaf-spring 83, which bears against the rear of the hook 73 and against the rear wall of the housing, and thus tends to throw 100 the hook 73 forward into cover-locking position. The normal position of the hook 73 is therefore a forward position; and, in order that the hook may not interfere with the closing of the cover, the upper forward edge 105 of the housing 81 on the casing-body is slightly bent out, as at 84, to form a cam, which, by engagement with the nose of the hook as the cover is closed, will force the hook rearward to allow the same to enter the housing 81. The nose of the hook may also be tapered, as at 85, to assist in this camming operation. The head 77 on the hook-engaging end of the pin 75 not only 110 serves as a wide flat surface for operating 115

the hook, but also serves as a shoulder to prevent the pin from being ejected forward out of the casing-wall by the spring-action of the hook 73, and from falling out when 5 the casing is tilted. The front and rear walls of the housing may serve as stops to limit the throw of the hook.

Variations may be resorted to within the scope of the invention, and portions of the 10 improvements may be used without others.

Having thus described my invention, I claim:

1. In combination with a sound-deadening casing for a typewriting machine having sound-sealing relations with certain parts of the machine to permit operation of the machine by parts thereof projecting to the outside of the casing, means for locating the feet of the machine to maintain such sound-sealing relations, said locating means comprising a bar pivoted at one end to the casing, and means for locking the bar. 15

2. In combination with a sound-deadening casing for a typewriting machine having sound-sealing relations with certain parts of the machine to permit operation of the machine by parts thereof projecting to the outside of the casing, means for adjustably locating the feet of the machine to maintain such sound-sealing relations said locating means comprising a device pivoted to the casing, and having means for locking the same in different positions to which it 30 may be set. 35

3. In combination with a sound-deadening casing for a typewriting machine having sound-sealing relations with certain parts of the machine to permit operation of the machine by parts thereof projecting to the outside of the casing, means for locating the feet of the machine to maintain such sound-sealing relations, said locating means comprising a pair of pivoted bars, recessed 40 to receive corresponding feet of the machine means for securing the same against said feet, and locating means for the remaining feet. 45

4. In combination with a sound-deadening casing for a typewriting machine having sound-sealing relations with certain parts of the machine to permit operation of the machine by parts thereof projecting to the outside of the casing, means for locating the feet of the machine to maintain such sound-sealing relations, said locating means comprising a bar pivoted at one end to the casing and at its other end having a pin-and-slot engagement with a lug on the casing, and means for anchoring the bar with the pin in any desired adjusted position lengthwise of said slot. 50

5. In combination with a sound-deadening casing for a typewriting machine having sound-sealing relations with certain parts

of the machine to permit operation of the machine by parts thereof projecting to the outside of the casing, means for locating the feet of the machine to maintain such sound-sealing relations, said locating means 70 comprising a bar of substantially right-angular formation, pivoted at one end to the rear of the casing and having its other end adjustably secured to the side of the casing. 75

6. In combination with a sound-deadening casing for a typewriting machine having sound-sealing relations with certain parts of the machine to permit operation of the machine by parts thereof projecting to the outside of the casing, means for locating the feet of the machine to maintain such sound-sealing relations, said locating means comprising a strip pivoted at one end to the casing, a lug on the casing, and means for securing the other end of the strip to said lug. 80

7. In combination with a sound-deadening casing for a typewriting machine having sound-sealing relations with certain parts of the machine to permit operation of the machine by parts thereof projecting to the outside of the casing, means for locating the feet of the machine to maintain such sound-sealing relations, said locating means comprising a strip of resilient sheet-metal material of substantially right-angular formation, pivoted at one end rearward of the casing, a bracket extending laterally of the casing, against which the other end of the strip is adapted to bear, a pin-and-slot connection between the bracket and the strip, means for securing the strip to the bracket in any desired setting of the pin along the slot, and a recess in the strip to receive the side of the foot of the machine. 100 105

8. The combination with a casing for a typewriting machine, of a lining-sheet of sound-deadening material for the casing, and a stiffening integral rib or flange on the interior of the casing and extending around its sides and back and turned up at its inner edge and forming with the wall of the casing a channel receiving and holding the lower edge of the lining-sheet. 110

9. The combination with a die-casting 115 forming a four-sided casing body for a typewriting machine, of a sheet of sound-deadening lining-material therefor, and an internal flange or rib forming part of the casting, extending peripherally therealong on all 120 sides of the base thereof, and having a turned-up inner lip and forming with the wall of the casting a U-shaped channel into which one edge of the lining-sheet is compressed and thereby held. 125

10. In a sound-deadening casing for a typewriting machine having a frame, supporting feet at the corners of the frame, a carriage and an operating finger-piece projecting from the carriage, said casing hav- 130

ing a slot along which said finger-piece travels with the carriage, and fixed means to cooperate with the front feet to position the machine to avoid interference with the operation of the finger-piece in the slot; means for engaging the rear feet to hold the front feet in engagement with said fixed means, and comprising for each rear foot a lug projecting forwardly from the rear wall of the casing, a bracket having a rear arm pivoted on said lug to swing horizontally, a concave portion to receive the adjacent foot and a lateral arm, a lug on the side wall adjacent said lateral arm, and means to clamp said lateral arm to the second-mentioned lug in adjusted position.

11. In a casing for a typewriting machine, a body comprising a die-casting having a flange or rib extending peripherally thereof at the base and forming with the inner face of the wall of the casing a channel to receive the lower edge of a lining-sheet of sound-deadening material, and lugs extending inwardly from the rib at the sides and at the rear to provide means for attaching locators for the rear feet of the machine.

12. In a casing for a typewriting machine, a body comprising a die-casting having a flange or rib extending peripherally thereof at the base and forming with the inner face of the wall of the casing a channel to receive the lower edge of a lining-sheet of sound-deadening material, and lugs extending inwardly from the rib at the sides and at the rear to provide means for attaching locators for the rear feet of the machine, said lugs being flat, those on the side walls lying in a vertical plane, and those on the rear wall lying in a horizontal plane extending through the lower parts of the lugs on the side walls.

13. In a sound-deadening casing for a typewriting machine, a base, and a body-portion formed of a die-casting having at its lower edge a continuous rib turned inwardly and upwardly to form with the wall of the casing a channel to receive one edge of a lining of sound-deadening material, and having a groove on the bottom thereof to receive the edges of the base.

14. In combination with a sound-deadening casing for a typewriting machine having sound-sealing relations with certain parts of the machine to permit operation of the machine by parts thereof projecting to the outside of the casing, said casing having fixed locators for the front feet of the machine, and also having a rear fixed wall, and independently adjustable locators mounted on said rear fixed wall and cooperative with each other for the rear feet of the machine, and releasable means for fastening the movable locators.

15. In a casing for a typewriting machine, a body comprising a die-casting hav-

ing a flange or rib extending peripherally thereof at the base and forming with the inner face of the wall of the casing a channel, said body including sides and a back and also including a front wall rising under the key-levers of the machine, and said rib extending entirely around said back and front wall and said sides, and a lining-sheet of sound-deadening material set down into said channel.

16. In a sound-deadening casing for a typewriting machine having a body-part with an open top through which the machine may be placed into the casing, said casing, having a front wall, and a fixed rear wall, locators on said front wall to engage the front feet of the machine to locate the machine within the casing when it is moved forwardly in said casing against said locators, a set of adjustable devices upon said rear fixed wall and independently operable after the machine has been located to engage the rear feet to hold the machine against accidental displacement within the casing, and individual means to lock the holding devices in effective position.

17. In a sound-deadening casing for a typewriting machine having a body-part with an open top through which the machine may be placed into the casing, said body-part having a front wall, side walls and a rear wall, locators on said front wall to engage the front of the machine to locate the machine within the casing when it is moved forwardly in said casing against said locators, devices pivoted on the rear wall and swingable inwardly after the machine has been located to engage the rear of the machine to hold said machine against accidental displacement within the casing, and devices on said side walls to lock the holding devices in their effective positions.

18. In a sound-deadening casing for a typewriting machine having a body-part with an open top through which the machine may be placed into the casing, said body-part having a front wall, locators on said front wall to engage the front feet of the machine to locate the machine within the casing when it is moved forwardly in said casing against said locators, two L-shaped holding devices, each having a substantially slanted corner, said holding devices being pivoted on the casing and behind the rear feet of the machine, so that they may be swung inwardly against the rear feet and accommodate themselves to the positions of the rear feet by means of their slanted corners, and devices on the casing and at the sides of said rear feet to lock said holding devices in their holding positions.

19. In a sound-deadening casing for a typewriting machine having a body-part with an open top through which the ma-

chine may be placed into said casing, said casing having a front wall, semi-circular locators on said front wall to engage the feet of the machine to locate the machine within the casing when it is moved forwardly in said casing against said locators, articulated holding devices swingable after the machine has been located to engage the rear feet of the machine to hold said machine against accidental displacement 10 within the casing, and means to lock the holding devices in their effective positions.

GEORGE W. CAMPBELL.
